Patented Feb. 17, 1914.

UNITED STATES PATENT OFFICE.

MARK JOSEPH O'REILLY, OF GIRARD, KANSAS.

SILO AND ROOF CONNECTOR.

1,087,394.

Specification of Letters Patent. Patented Feb. 17, 1914.

Application filed August 11, 1913. Serial No. 784,184.

To all whom it may concern:

Be it known that I, MARK J. O'REILLY, a citizen of the United States, residing at Girard, in the county of Crawford and State 5 of Kansas, have invented certain new and useful Improvements in Silo and Roof Connectors, of which the following is a specification, reference being had therein to the accompanying drawing.

10 This invention relates to a silo roof support and has special reference to that type of silo roof supporters that efficiently support the rafters of a silo roof and at the same time provide for the ventilation of the 15 silo.

Another object of this invention is the production of an efficient rafter support that can easily be detached from the body of the silo.

20 A still further object of this invention is the production of a device adapted to tighten the top hoops of the silo to make the silo air-tight and at the same time will not affect the roof thereof.

25 With these and other objects in view this invention consists of certain novel combinations, constructions and arrangements of parts as will be hereinafter fully described and claimed.

30 In the accompanying drawings: Figure 1 is a vertical section of the top portion of the silo with the improved roof support mounted thereon. Fig. 2 is a top plan view of the improved roof support mounted on 35 the silo. Fig. 3 is a perspective view of the improved roof support. Fig. 4 is a perspective view of the rod clamping means used with this invention. Fig. 5 is a vertical section of one of the securing plates.

40 Referring to the parts by reference numerals 10 denotes an ordinary silo having mounted thereon a clamp member consisting of a bridge 11 and downwardly depending side members 12, said side members being provided with alined openings 13. Passing through the alined openings 13 of the downwardly depending side 12 of the clamp member is a U-shaped clamp 14 having

secured on its inner end a clamp plate 15. Between the curved end of the member 14 and 50 the clamping plate 15 are top hoops 16 adapted to hold the silo in correct shape. This clamping member 14 can be adjusted to said hoop 16 by means of the nuts 17 threaded on the inner end of the member 14. 55

The threaded pin 18 having an eye 18' at its upper end has a rod 19 positioned therein. The plates 20 are provided with openings 21 having formed intermediate their length the pocket 22. Fitting in said pocket 22 of 60 the plate 20 are the ends of the rod 19 and the plates are held on the rod 19 at one end by means of the head 23 and at the opposite end by means of the nut 24.

It will be seen from the foregoing de- 65 scription that this support for the rafters of the silo roof is very substantial and at the same time by means of the top hoop clamping means shown and described, the silo can be made air-tight. This top hoop 70 clamping means may be operated independently of the rafter support. It will also be seen that the support can be easily and quickly taken down and re-placed.

It is obvious that minor changes may be 75 made in the form and construction of this invention without departing from the spirit of the same. It is, therefore, not wished to confine the invention to the exact form herein shown and described but it is wished to 80 include all such as come within the scope claimed.

What is claimed, is:

In a silo the combination with a body, of a roof supported thereon comprising a plurality of diverging roof beams, a plurality of clamping plates secured to said roof beams near the outer ends thereof for allowing easy access thereto and being spaced from each other, said plates provided with bulged 90 portions intermediate their ends, a tie-rod having its respective ends positioned within said bulged portions of said plates, binding nuts carried by the respective ends of said rod for firmly clamping the same in engagement with said plates, a substantially 95

inverted U-shaped clamp fitting over the upper end of said body, a pin extending at an angle from the upper end of said substantially U-shaped clamp, said pin provided 5 with an eye for receiving said connecting bar, and means passing transversely through said substantially inverted U-shaped clamp and through said body for firmly holding

said U-shaped clamp in a set position upon said body.

In testimony whereof I hereunto affix my signature in presence of two witnesses.

MARK JOSEPH O'REILLY.

Witnesses:

J. J. GEORGE,
A. F. LA FORCE.
